CONTACTOR FOR ALARM AND SIGNAL CIRCUITS

Ole A. Jacobson, Grand Rapids, Mich., assignor, by mesne assignments, to American District Telegraph Company, Jersey City, N. J., a corporation of New Jersey

Application May 24, 1928, Serial No. 280,233

13 Claims. (Cl. 177—314)

This invention relates to contacting or control means for alarm and signal circuits, and is more especially intended for use in bank protection systems, as shown in my co-pending application, 5 Serial No. 53,768, filed August 31, 1925.

The main objects of this invention are to provide hidden alarm sounding and lock-operating means which will be inadvertently operated by some act of the robber, or by some act ordered 10 by the robber in attempting to gain admission to the teller's cage or like prohibitive areas, so that the bank operators will not have to make any moves which might appear suspicious to the robber.

15 The door to the teller's cage and the area around the vault is usually provided with a spring lock which is operated by a handle from the inside of the cage or area, and which is operated by means of a key from the outside. To 20 gain admission, the robber usually orders someone inside the cage to open the door, or orders the person known to have the key to give it up or to use the key to unlock the door from the outside.

25 In this invention, a spring lock is provided having a switch and selective means so arranged that, by persons cognizant of the hidden means, the lock may be operated by the handle or the key in the ordinary course of business without 30 causing an alarm, but which may be operated in what is apparently the usual and correct manner by said persons so as to cause the alarm.

An illustrative embodiment of this invention is shown in the accompanying drawing, in 35 which:—

Figure 1 is a view of the interior of the door lock, the cover being removed and parts shown in section together with a diagrammatic representation of an alarm and signal circuit connected to the lock.

Fig. 2 is a cross section of the lock taken on the line 2—2 of Fig. 1.

Fig. 3 is a cross section on the line 3—3 of Fig. 1.

45 Referring to the drawing, the lock casing, or housing 1, is provided with cover 2 which is removably secured to the casing by means of the screws 3 in the usual manner. The lock is mounted in the door 4, as indicated by dotted lines in Fig. 2, with the handle 6, which is rotatably mounted in the housing 1, projecting from the inner side of the door, and the lock tumbler 7, which is rotatably mounted in the hub 8 50 formed on the cover 2, accessible for the inser-

tion of the key 9 from the outer or opposite side of the door.

The lock bolt 10 is slidably mounted in the housing 1 to project from one side thereof for engaging the door latch or keeper, not shown. The bolt is retained in position by the screw 11 which projects through the slot 12 formed in the body portion of the bolt 10 and threads into the bottom wall of the casing 1. The bolt 10 is resiliently pressed outwardly by means of the spring 13 which is housed in a hollow portion of the bolt 10, as shown, and bears against the post or stem of said screw 11.

The bolt 10 is notched on the lower side within the housing to provide the shoulders 14 and 15, 15 which are engaged respectively by the bar 16 which is connected to the handle 6, and the cam finger 17 which is attached to the inner end of the tumbler 7 for withdrawing the bolt into the housing to unlock the door.

The shank 18 of the handle 6 is hollow, and is slotted transversely at the inner end as is more clearly shown at 18' in Fig. 1. A short rod 19 fits slidably at 18' in the hollow shank 18 and terminates in an angular projecting trigger 20 25 which is accessible, as by a finger of the hand of an operator, through a suitable recess 20' provided on the inner side of the handle 6. An extension 20a of this recess communicates with the bore 18'. The rod 19 extends through a hole in the center of the bar 16, as seen in Figs. 1 and 2, and the bar is retained on the rod by means of the lock nuts 21 which are threaded on the inner end of the rod. The bar is slidably engaged in the slot 16', and is pressed inwardly towards the end of the shank by means of the spring 22 which seats in an enlargement of the bore 18' on a shoulder 18a of the shank and presses against the bar. Thus the bar is normally held in position near the end of the shank, but 40 may be drawn close to the bottom wall of the casing by pressing on trigger 20.

The end of the bar 16 which is related with the shoulder 14 of the bolt 10, is of sufficient width, as shown in Fig. 2, to ensure that the 45 shoulder is engaged by the bar in both the extended and the retracted positions. Thereby motion is communicated from the handle 6 to withdraw the bolt whether the handle is merely grasped and turned, or whether the trigger is 50 depressed and held while the handle is turned, which latter is the proper manner of operating the lock; that is to say by those who are aware of the presence of the hidden trigger.

The opposite or lower end of the bar 16 is 55

aligned for engaging relation with a projecting shoulder 23, formed on the signal bolt 24, in the normal or extended position of the trigger, but said end passes freely under said shoulder portion when trigger is depressed, as becomes clearly evident on an inspection of Figs. 1 and 2. The signal operating bolt 24 is slidably mounted in the casing 1, and is guided and retained in position by the pin 25, and by the cap screw 26 10 which are fixed in the casing and engaged in suitable slots formed in the said signal bolt. See Fig. 1.

The bolt 24 is pressed rearwardly by means of the spring 28 which is housed in the bolt and bears against the pin 25. The bolt 24 is also provided with a spring pressed detent ball 29 which rides on a shouldered surface 30 of the housing 1, so that cognizant persons are apprised by the turning resistance of the handle when the 20 signal is not thrown off.

When the signal bolt 24 is moved, it makes contact through the medium of a shoulder thereon, as shown in Fig. 1, with a switch finger 31, which is mounted on an insulating block 32, and this block is secured to the side wall of housing 1 and connected to one side 33 of the signal and alarm circuit, the opposite side 34 of which is grounded or connected to the metal of the casing 1. This circuit may include any suitable 30 translating means such as the alarm A.

A second finger 35 is joined to the finger 31, and terminates opposite the inner end of the lock tumbler 7. See Fig. 3. The key 9, for operating the tumbler 7 is provided with a projection 36 at one side of the inner end, which strikes against the surface of the cam 17 when the key is inserted in the position shown in Fig. 3. In this position the tumbler can be turned to rotate the cam for withdrawing the bolt, but the key is prevented 40 from contacting with the finger 35. It is therefore only necessary for an authorized or informed person to keep the projection 36 uppermost, and this position is further seen to be correct when the inner notch 9a of the key is at the 45 end of the hub 8. In the reverse position of the key, when the notch 9' is at the end of said hub, the end 36 passes through a slot 39 in the cam 17; and makes contact with the finger 35. Keys have heretofore been provided with notches or 50 projections at one or both sides, and since it is usual to insert all of these notches in the hub, it follows that an unknowing person may do likewise in this case. But when the notch 9' is inserted the projection 36 engages the contact 55 to close the circuit and sound the alarm A.

In operation, cognizant persons may operate the lock from either side of the door by holding the trigger 20 depressed while turning the handle 6, or by inserting the key 9 with the projection 60 36 at the upper side. In case they are commanded by the robber to operate the door, they can grasp the handle in the ordinary manner and open the door and at the same time energize the signal circuit without making any suspicious or unusual motions. If the person is on the outside of the cage, he can insert the key in the reverse position, which cannot be detected by the robber, and also sound the alarm in unlocking the door.

70 It may be seen that the lock may be operated independently of the switch while the switch is dependent for operation upon the manner of inserting the key or, if desired, upon the construction of the key. For example, separate keys may 75 be provided, one of which is suitable for operating

only the lock and another suitable for operating both the lock and the switch.

While but one specific embodiment of this invention has been herein shown and described, it will be understood that details of the construction shown may be altered or omitted without departing from the spirit of this invention as defined by the following claims.

I claim:

1. In combination, a lock having a bolt, a handle on one side only, and a key hole on the other side only, and means whereby the bolt is controlled by said handle and by a key inserted in said hole in normal lock-controlling position; said key hole also receiving the key in a reverse 15 lock-controlling position simulating normal operating position; an alarm means operated by normal operation of the handle for unlocking the bolt, and by said key when in said reverse position; means including a manual trigger on the handle for preventing operation of the alarm means by the handle during normal operation of the key.

2. In combination, a lock having a bolt, a handle on one side only, and a key hole on the other side only, and means whereby the bolt is normally controlled by said handle and by a key inserted in said hole in normal lock-controlling 30 position; said key hole also receiving the key in a reverse lock-controlling position simulating normal operation position; an alarm means operated by normal operation of the handle for unlocking the bolt, and by said key when in said 35 reverse position; and means including a trigger on the handle for selectively preventing operation of the alarm means by the handle during handle-operation of the bolt.

3. In combination, a lock having a bolt, a handle on one side only, a reversible key and a key hole on the other side only, selectively operable alarm means, and means whereby the bolt is controlled by said handle or by said key when inserted in said hole, said key adapted to operate 45 the bolt of said lock in either its normal or reverse positions, and means including a switch operable when the key is inserted in the reverse position for operating said alarm.

4. In combination, a lock having a bolt, a selectively operable alarm including a circuit having a switch, a handle on one side of the lock for operating the bolt, a reversible key, a lock cylinder on the opposite side of said lock for receiving said key in one of two operating positions, said key 55 in one of said positions forming part of said circuit, and means on said handle for preventing contact with said switch when said handle is operated to operate said bolt.

5. In combination, a lock comprising a casing 60 of conductive material including a bolt, and a handle, said handle having therein a recess; an insulated conductor in said casing; a switch member cooperating with said casing adjacent said conductor; means carried by said handle 65 within said casing and movable between two positions relative to said handle for operating said bolt, said means when in one of said positions being adapted to move said switch member to said conductor, and manipulable means rigid with 70 the first mentioned means and disposed in said recess whereby to selectively move the first mentioned means into the other position for operating said bolt independently of said switch member.

6. In combination a lock having a key and means for guiding the key into the lock in two different positions on the same side of the lock; means on the key for unlocking the lock in both of said positions; a signal means; and means on the key for operating the signal means when the key is in one of said positions only.

7. In combination, a lock having guide means for guiding a key therein; a key guided in the lock by said guide means in either of two positions of the key and having a terminal projection at the inner end of one side edge; means actuated by said guide means for operating the lock; an electrically conductive contact member engageable by said projection when said key is inserted in one of said positions; and means engaging said projection when the key is guided in the other position and holding the key out of contact with the contact member.

8. In combination, a lock casing to which a conductor may be connected; a bolt slideable therein; an elongated rotary tumbler grounded on the casing and rotatably mounted in the casing and having a groove in one side extending through both ends; a cam finger secured around the inner end of the tumbler and engageable with the bolt to retract the bolt; an electrically conductive insulated contact member, to which a conductor may be connected, positioned near and opposite the inner end of the groove; and a key slideable in said groove and having at the inner end of one side a terminal projection engageable with the finger when said side is uppermost in the groove to hold the key from the contact, and constructed and arranged to project from the end of the groove and engage said contact member when said side is at the bottom of the groove.

9. In combination, a lock of conductive material having guide means for guiding a key therein; a key guided in the lock by said guide means in either of two positions of the key and having a terminal projection at the inner end of one side edge; means actuated by said key for operating the lock; an electrically conductive insulated contact member engageable by said projection when said key is inserted in one of said positions; means engaging said projection when the key is guided in the other position and holding the key out of contact with the contact member; and a signal circuit electrically connected to and between said lock and contact.

10. In combination, a lock casing; a bolt slideable therein; an elongated rotary tumbler rotatably mounted and grounded in the casing and having a groove in one side extending through

both ends; a cam finger secured around the inner end of the tumbler and engageable with the bolt to retract the bolt; an electrically conductive insulated contact member positioned near and opposite the inner end of the groove; a key slideable in said groove and having at the inner end of one side a terminal projection engageable with the finger when said side is uppermost in the groove, and adapted to project from the end of the groove and engage said contact member when said side is at the bottom of the groove; and a signal circuit electrically connected to and between the casing and said contact.

11. In combination, a lock having a key and means for guiding the key into the lock in two different positions on the same side of the lock; cooperating means on the key and in the lock for unlocking the lock in both of said positions; a signal means; operating means for operating the signal means; and means on the key for operating the operating means, when in a certain one of said positions to cause the operating means to operate the signal means only when the key is in one of said positions; said means on the key being constructed to leave the operating means inoperative when the key is in the other of said positions.

12. In combination, a lock having a key and guide means for guiding the key into the lock in two different positions on the same side of the lock the key being so constructed that it may be guided by the guide means in said two positions; cooperating means on the key and in the lock for unlocking the lock in both of said positions; a signal means; operating means for operating the signal means; and means on the key for operating the operating means in one of said positions only to cause the operating means to operate the signal means, when the key is in one of said positions only.

13. In combination, a lock having a key and means for guiding the key into the lock in two different positions on the same side of the lock, the key being so constructed that it may be guided by said guide means when the key is in certain of said two positions, cooperating means on the key and in the lock for unlocking the lock when the key is in either of said positions; an operating means; a translating means operable by the operating means; and means on the key for operating the operating means in one of said positions exclusively, to cause the operating means to operate the translating means when the key is in one of said positions only.

OLE A. JACOBSON. 55
